UNITED STATES PATENT OFFICE

WILLIAM C. JOHNSON, OF MILWAUKEE, WISCONSIN, ASSIGNOR TO MACHINERY DEVELOPMENT COMPANY, OF MILWAUKEE, WISCONSIN, A CORPORATION OF WISCONSIN

SETTING OUT BOARD

Application filed September 15, 1928. Serial No. 306,247.

The invention relates to setting-out boards for use in setting out leather, more particularly where the hide is allowed to dry in set-out condition on the board.

5 Heretofore setting-out boards have been made of cardboard or fibre board. Such boards warp and buckle and cannot be readily used where the setting-out process is accomplished by machinery and do not stand up 10 under the rough usage to which devices of this kind are subjected. To obviate the above mentioned difficulties, the object of this invention is to provide a setting-out board in which the foundation portion or core is of 15 metal, preferably aluminum, to which a yieldable facing of paper, fabric or the like is secured, which facing is rendered impervious to the water or adhesives used in the setting-out operation by coating said facing 20 with lacquer, varnish or the like.

In the drawings Fig. 1 is an elevation view of a setting-out board embodying the invention, with a hide in set-out position thereon;

25 Fig. 2 is a vertical sectional view through the board itself taken on the line 2—2 of Fig. 1.

Referring to the drawings the numeral 4 designates the main body or core of the board 3 and is of metal, preferably aluminum, by 30 which I mean aluminum or aluminum alloy. Applied to this core, on each side thereof, is a facing layer 5 of suitable yielding material, preferably fibrous material such as paper, fabric or the like, and to render said facing 35 impervious to water or adhesive used in the setting-out process the same is provided with an impervious coating 6 which may be a suitable lacquer, varnish or the like.

40 The manner of using said setting-out boards is, of course, known. A hide 7 is placed on the board 3 in a moist condition, either with or without adhesive, and is then set out thereon either by hand tools or suitable mechanism. The board with the hide set 45 out on one side thereof is then turned over on its supporting table and another hide set out on the opposite side thereof, after which the board with the hides set out thereon is removed from the table and placed in a dry- 50 ing rack or otherwise stored until the hides

thereon have dried on the board in a set out condition.

The board above described is rigid and will not buckle or get out of shape, as is the case with the portable setting-out boards heretofore known. Furthermore, this board will stand more abuse and rough handling than boards of known construction and the skins adhere to the board better than to known forms when one skin is between the board 60 and table while the operator is pasting another skin on the opposite side of the board.

I desire it to be understood that this invention is not to be limited to any particular form or arrangement of parts except insofar 65 as such limitations are included in the claims.

What I claim as my invention is:

1. A setting-out board for leather comprising a sheet metal body portion, a facing of fibrous material attached to said body portion over the working surface thereof, the said fibrous material having a smooth surface and being coated with an impervious coating of varnish or lacquer.

2. A setting-out board comprising an aluminum plate, a facing of fibrous material attached thereto over all portions of its working surface, the said fibrous material having a smooth surface and being coated with an impervious coating.

In testimony whereof, I affix my signature.

WILLIAM C. JOHNSON.
